[57] CLAIM

The ornamental design for a jar or the like, as shown and described.

DESCRIPTION

FIG. 1 is a top perspective view of a jar or the like showing my new design;

FIG. 2 is an elevational view, the opposite side being
the same in appearance;

FIG. 3 is a top plan view; and

FIG. 4 is a bottom plan view thereof.

FIG. 2

FIG. 1

FIG. 3
